ELECTRON TUBE COOLING SYSTEM

Nils E. Lindenblad, Port Jefferson, N. Y., assignor,
by mesne assignments, to Radio Corporation of
America, New York, N. Y., a corporation of
Delaware

Application March 15, 1935, Serial No. 11,217

5 Claims. (Cl. 250—27.5)

My invention relates to cooling systems for thermionic discharge devices and is particularly concerned with air cooling means for high powdered radio tubes.

5 High power radio tubes are usually cooled by water circulated thru water jackets placed about the exposed metal portions, such as the cylindrical anodes of the transmitter type of tube. Water cooling has some disadvantages, such as 10 the difficulty and expense of making the cooling system water tight. Leaks in the water system dampen the exterior surfaces of the tube and may create objectionable leakage paths for the high potentials applied to the tube. The water 15 feed pipes to the anodes, which are usually at high potentials above ground, provide comparatively low resistance paths to the circuit between the anodes and ground. Further, the usual water cooling jackets surround only a portion of 20 the anode and do not cool directly the glass of the tube or the glass-to-metal seals between the anode and the glass envelope. It is particularly important that these seals be cooled since tube 25 failures may result at high temperatures from unequal expansion of the glass and metal at the seal.

An object of my invention is to provide an improved cooling system for thermionic discharge devices.

30 A further object of my invention is to provide for radio tubes an air cooling system that gives more complete and uniform dissipation of heat.

A still further and more specific object of my invention is to provide a cooling arrangement 35 which cools not only the glass and metal portions of the tube, but also the glass-to-metal seals between the glass and metal parts.

In accordance with my invention I provide the exposed metal portions of the tube, such as the 40 anode and grid terminals, with radiating members and circulate air, preferably under pressure, over the radiating members. In one embodiment of my invention the radiating member forms an integral part of an electrical tuning 45 circuit for the tube.

A more complete understanding of my invention will be had by referring to the accompanying drawings in which Figure 1 shows one form 50 of tube embodying my invention; Figure 2 shows a cross section along line 2—2 of Figure 1; Figure 3 is a bottom view of the tube and cooling means shown in Figure 1; Figure 4 shows my invention applied to a second form of tube; Figure 5 shows my invention applied to an ultra- 55 short wave oscillator; Figure 6 is a sectional view

along the line 6—6 of Figure 5; Figure 7 shows a slightly modified form of my cooling radiator applied to a standard tube; and Figure 8 is a section along the line 8—8 of Figure 7. Throughout the drawings, like parts are indicated by similar reference characters.

Figure 1 shows a conventional type of high power tube having an envelope consisting of a glass portion 1 and a cup-shaped metal anode 2 sealed at its edge to the glass portion of the envelope. The upper end of the envelope carries cathode leads 3, and the side wall of the glass portion is protruded, as at 4, to form a base for a grid terminal member 5 of any standard construction and hermetically sealed into the protuberance 4. Integral with the terminal 5 is an outwardly extending pin 6 to which is usually connected the external grid lead.

In applying my invention to this form of tube 20 the anode and the grid terminal, and also the seals, if desired, are air cooled. For cooling the grid terminal the grid lead is replaced by a hollow cup-shaped sleeve 7 with a conical exterior surface fitted over the pin and secured to it 25 either by a ground fit or by the sweating in of some heat conducting adhesive, such as lead, as shown at 8. An outer radiating member 9 with a turned out conical recess conjugate with the external surface of the sleeve member is secured to 30 the outer surface of the sleeve member 7 by a bolt 10. Extending longitudinally thru the radiating member 9 is a series of circularly arranged holes or cooling ducts 11 terminating at their inner ends adjacent the grid terminal 35 member 5. For directing the cooling air to the grid terminal seal I prefer to secure to and around the radiating member a cylindrical skirt-shaped shield 12 which may be held in position as by a frictional fit or by welding. The left or inner end of the skirt is flared as shown at 13 to permit the ready exhaust of air from ducts 11. To 40 the radiating member is fastened a suitable grid lead connector 14, and to the outer end of the radiating member is secured a short section of 45 insulating pipe 15, formed of glass or "bakelite" for example, which in turn is connected at one end to an air supply duct 16, which in turn may be formed of insulating material, such as rubber hosing. Air duct 16 is connected to the outlet 50 of any suitable air pump or fan for delivering air under any desired pressure to the inlet ends of duct passages 11. The air in passing thru ducts 11 serves to cool the radiating member 9, 55 which in turn cools the contacting metallic parts

of the pin and terminal member. The air upon leaving the inner ends of the duct passages 11 flows against the glass walls of the envelope and protuberance 4 and against the glass-to-metal seal between the terminal member and protuberance. It will be noted that by this construction the terminal member and its pin are cooled by the same stream of air which cools the glass and its seal to the metal, thus minimizing the difference of temperature between the adjacent glass and metal parts. By maintaining the temperatures of these parts nearly equal, unequal expansions or contractions between the glass and metal are reduced, thus minimizing fractures at the seal.

The anode 2 of the tube is provided with radial cooling fins 17 which may be formed integral with the anode or fabricated upon a sleeve ground internally to make intimate contact with the outer surface of the anode. As best shown in Figure 3 air under pressure is introduced tangentially thru an air supply pipe or duct 18 to the spaces between the radial fins and exhausted thru an opening at 19. Air pipe or channel 18 may be formed of insulating material such as glass, rubber or bakelite. It will be noted that all mechanical connections between the high potential contacts and electrodes of the tube and the air pumps are thru insulating pipes which are inherently kept dry, and consequently free of leakage paths, by the presence of a stream of air under pressure.

In Figure 4 I have illustrated my invention as applied to a slightly modified form of power tube. The anode 2 is provided with two oppositely extending glass sleeve portions 1, and in the upper end of the upper glass sleeve is sealed cathode lead wires 3. Surrounding glass portions 1, of the tube are hollow annular ring members 30, which in vertical cross section are rectangular in outline as shown. The rings are positioned concentrically with the cylindrical envelopes 1, and are spaced therefrom along all radial lines thru the envelope. In the inner wall of each ring member intermediate its ends is a circumferential opening or recess 31. At one side and exteriorly thereof is constructed an inlet air duct nipple 32 which serves to support the ring members upon the supporting panel 33. The tube body may be supported within the ring members and centrally fixed therein by end plates 34. To the ends of the nipples 32, are suitably secured air supply pipes 35, which are connected to an air supply source thru the pipe 36. Air under pressure entering at 36 divides into passages 35, and flows thru nipple members 32. From the interior of the annular ring members, the air is directed forcibly against the walls of the envelope and deflected upwardly and downwardly towards the ends of the annular members. As is evident from the drawings, one-half of the exhausted air flows against the metal parts of the anode 2, the other half circulating about the end electrode terminals.

In Figures 5 and 6 I illustrate how my improved cooling system may be extended to form part of the oscillatory system of a short-wave oscillator or amplifier. Power tubes 1, with their anodes 2 (Figure 6) are so related as to constitute a conventional push-pull amplifier or oscillator for ultra-short waves which may be operated for example on the Barkhausen-Kurz principle. In the construction illustrated in Figure 5 the heat radiating members comprise the tuning Lecher wires for the stage. As in Figure 1 a sleeve 40 is

fitted over the outer surface of the cylindrical anodes. On the sleeve member is formed circular cooling fins 41 which extend circumferentially of the sleeve. Radial fins 41 are cast with extensions or radiating members 42 and 43, which in general are narrower than the diameter of the circular portions thereof and are extended radially outward in opposite directions a distance substantially greater than the diameter of fins 41. The edges of the fins 41, 42 and 43 are covered by plates 43 which extend the full length of the fins, thus forming a plurality of parallel rectangular air passages. At one end of each of the fins 42 is introduced air under pressure which passes thru the ducts around the anode and out the opposite ends of the air passages. Radiating members 42 and 43, when formed of any good heat conducting material such as metal, may be employed as long lines or Lecher wires to electrically tune the tubes. By means of sliding bars 44, in combination with condenser 45, the tubes may be adjusted to resonate at any desired operating frequency.

In Figures 7 and 8 is shown a further modification of my cooling system as applied to a conventional transmitting tube. To the cylindrical or cup-shaped anode 2 is secured a hollow conical shaped cup member 50, which may be either ground fitted to the anode or sweated thereon with solder 51 as described above in connection with member 7 of Figure 1. Fitted over the conical exterior surface of the sleeve 50 is secured cup-shaped member 52, by a bolt 53. Formed integral with the cup-shaped member 52 to extend from one side thereof is a bar or rod 54. Member 54 may take any desired cross sectional form which by way of example is shown as circular in Figures 7 and 8. Extending longitudinally thru the bar is a series of circularly arranged air ducts 55, which at their inner ends terminate adjacent the cup-shaped member 52. 56 is a hollow cylindrically shaped skirt member positioned concentrically about the bar 54, and to form an annular space 59 is spaced from 54 by means of perforated end member 57. Air under pressure is introduced at the right hand end of the bar and skirt members from an insulating hose connection 58. Cup-shaped members 50 and 52, which are formed of any good heat conducting material, transmit most of the heat from the anode along the bar member 54 where it is dissipated in the air stream thru passages 55 and the annular space 59. The air from the exhaust end of the ducts 55 and annular passage 59 is directed against the glass of the envelope 1, against the glass-to-metal seal at the anode and against the grid terminal 5. With this arrangement of parts the entire transmitter tube including its anode and terminal members are effectively cooled from a single and inexpensive source of cooling air.

The characteristic feature throughout the various forms of my invention lies in the fact that the anodes, electrode terminals and glass-to-metal seals are cooled uniformly by a single source of cooling media and in the fact that the conduits for the cooling media provide high resistance paths between the parts of the tube and ground.

Having described my invention, I desire to be limited only by the prior art and by the appended claims.

What I claim as new is:

1. A thermionic discharge device comprising an envelope for enclosing cooperating electrodes, 75

- terminals for said electrodes extending exteriorly of said envelope and sealed in insulating material in the wall thereof, an apertured heat radiating member of good heat conducting material secured 5 to one of said terminals, means for introducing air under pressure at one end of the apertures, the other end of the apertures being positioned to direct the air against the envelope adjacent the seal.
- 10 2. An electron discharge device comprising a gas tight glass envelope for enclosing an electrode, an electrical connection for said electrode thru the wall of said envelope comprising a metallic terminal member of considerable bulk 15 sealed in the glass, a heat radiator on said member, means for cooling the glass-to-metal seal and said member comprising means for directing a stream of cooling fluid through said heat radiator and against the terminal member and 20 the glass adjacent thereto.
3. An electron discharge device comprising an impervious envelope with a vitreous wall, an electrode terminal member of metal sealed in 25 said wall of the envelope and extending exteriorly thereof, a heat radiating member secured to said member and in direct metallic contact therewith over a substantial portion of the surface of the terminal member, said radiating member being provided with air ducts, inlet means for introducing air under pressure to one 30 end of said ducts, the other ends of the ducts terminating adjacent the vitreous wall-to-metal seal.
4. A discharge device comprising a cylindrical anode closed and sealed at one end by a longitudinally extending cylindrical envelope of insulating material, cooling means for the anode comprising a cylindrical sleeve fitted snugly around said anode, circular cooling fins attached to and in good heat conducting relation with said sleeve, said fins having relatively narrow parallel 10 portions extending radially beyond the periphery of said circular cooling fins, closure means over the edges of said fins and their extended portions, and means for introducing air at the outer ends of the extended portions of said fins. 15
5. A thermionic discharge device comprising a cylindrical anode closed at one end, a tubular glass envelope hermetically sealed at one end to the open end of said anode, an electrode terminal sealed into the glass wall of said envelope, the 20 terminal being spaced from the anode-to-glass seal, a cup-shaped member of good heat conducting material fitted over and in intimate contact with the outer wall of said anode, said member having an outwardly extending bar with longitudinal 25 ducts, said ducts terminating at one end adjacent the cup-shaped member, a shield of substantially the same length as said bar and greater diameter placed concentrically about said bar, and means for introducing air at the outer 30 end of said bar and shield.
